(57) CLAIM

The ornamental design for a pedestal with interchangeable message panels, as shown and described.

DESCRIPTION

FIG. 1 is a front perspective view of a pedestal with interchangeable message panels showing my new design; FIG. 2 is a top perspective view thereof;

FIG. 3 is a front view thereof;

FIG. 4 is a back view thereof;

FIG. 5 is a right side view thereof;

FIG. 6 is a left side view thereof;

FIG. 7 is a top view thereof;

FIG. 8 is a bottom view thereof;

FIG. 9 is a cross-sectional perspective view thereof, taken across section-line 9-9 in FIG. 6; and,

FIG. 10 is another front perspective view of the pedestal with interchangeable message panels shown in a state of use. The broken lines depict portions of the article and environment that form no part of the claimed design.

1 Claim, 9 Drawing Sheets
